LETOFF FOR LOOMS

Wallace Hamilton, Albany, N. Y., assignor to
Draper Corporation, Hopedale, Mass., a corpora-
tion of Maine

Application November 21, 1946, Serial No. 711,403

7 Claims. (Cl. 139—110)

1
The present invention relates generally to let-off mechanisms for looms and, as illustrated herein, relates more particularly to a positive type of let-off mechanism wherein the warp beam is positively rotated to supply warp and wherein the let-off mechanism may be oscillated to provide for uniform warp tension.

Let-off mechanisms of the type above referred to usually comprise a warp beam geared to a transmitting shaft which carries a pinion driven from suitable mechanism connected to the loom and acts thereby to transmit the required movement of rotation to the warp beam. The warp beam is usually operated with a step-by-step forward motion to let off the warp. The rate of rotation of the warp beam is controlled by mechanism connected to the whip roll and other mechanism governed in accordance with the variation in diameter of the warp supply on the warp beam. Even when a vibrating whip roll is used, momentary increases or decreases in tension of the warp sheet may occur because of operation of the harness frames, improper operation of the let-off mechanism or for other reasons. Such variations in warp tension result in variations in cloth structure and appearance and consequently in lower quality of the cloth produced.

One object of the present invention, accordingly, is to provide an improved let-off mechanism for a loom wherein the warp sheet is maintained under substantially uniform tension during operation of the loom. To this end and in accordance with one feature of the invention, the loom is provided with a let-off mechanism which is arranged to oscillate the warp beam in response to increases and decreases in warp tension thus compensating for such variations and providing substantially uniform tension on the warp sheet at all times.

A further object is to improve generally upon the operation and construction of looms.

With the above and other objects and features in view, the invention will now be described with particular reference to the accompanying drawings which illustrate a preferred embodiment of the invention and in which:

Fig. 1 is a view in side elevation of a portion of a loom having the invention thereto applied.

Fig. 2 is a view in rear elevation of structure shown in Fig. 1;

Fig. 3 is an enlarged detail view of a portion of the let-off;

Fig. 4 is a sectional view taken along the line 4—4 of Fig. 1, the scale of Fig. 4 being somewhat greater;

Fig. 5 is a view of certain of the parts shown in

2
Fig. 1, as viewed from above in that figure, on a reduced scale;

Fig. 6 is a sectional view taken along line 6—6 of Fig. 2, with parts omitted for the sake of clarity; and

Fig. 7 is a sectional view taken along line 7—7 of Fig. 2, with certain parts omitted in the interest of clarity of illustration.

The present drawings show only a portion of the loom with the improved let-off mechanism applied thereto. The parts of the loom which are not shown are of usual construction and form no part of the present invention.

The present invention is illustrated as applied to a "positive" type of let-off mechanism which includes a warp beam geared to a transmitting shaft which is driven from suitable mechanism connected with the operating structure of the loom. The let-off mechanism to which the invention is shown applied in the illustrations is of the well known Roper type such as is illustrated in general form in Patents Nos. 647,815 to Draper et al.; 731,622 to Roper; 1,704,911 to Burnham, and 1,758,738 to Draper, but the invention is equally well adapted for employment in other types of let-off mechanisms.

The drawings show the rear right hand side of a loom which includes a side frame 10 having a suitable bearing 12 in which the right hand end of a shaft 14 is journaled. The shaft 14 supports a warp beam 16 holding a warp supply. A sheet of warp threads, 18, commonly called a warp sheet, extends from the beam to the weaving mechanisms of the loom. The warp beam 16 is arranged to be positively driven through a gear 84, preferably formed integrally with one head of the beam, meshing with a driving pinion 82 (Fig. 4). Driving pinion 82 is affixed to and rotated by a shaft 42 mounted for rotation in bearing means 42a mounted on a bracket 10a secured to the loom frame in any desired manner. At its opposite end shaft 42 carries affixed thereto a pawl wheel 111 carrying a pawl 112. Pawl 112 is spring pressed by a spring 113 into engagement with teeth 114 formed on a side face of a gear 78 mounted for free rotation on shaft 42. Gear 78 has a flange carrying internal gear teeth 78a. Referring to Fig. 6, gear 78 is arranged to be rotated by a planetary ring gear 76 which is 45 rotatably carried in an orbit around shaft 42 by an eccentric 74 on which the ring gear is slidably mounted. Ring gear 76 is restrained from free rotation about its own axis by laterally extending lugs 76a integral therewith which slidably 50 ride in slots 76b formed in a generally T-shaped member 80. Member 80 is, with an exception to

be fully explained hereinafter, restricted to reciprocal motion in a direction at right angles with a line interconnecting lugs 76a, with hub 72a sliding in a cut-out 80a formed in member 80.

Referring to Fig. 4, eccentric 74 is seen to be mounted for free rotation on shaft 42 and to have integrally formed therewith a sleeve hub portion 72a and a ratchet wheel 72 carrying ratchet teeth 72b on its periphery and a friction flange 72c. The previously mentioned centrally located cut-out or guideway 80a (Fig. 6) formed in member 80 closely engages the hub portion 72a of eccentric 74 with a sliding fit.

Referring to Figures 1, 4 and 7, there is mounted for rocking movement on shaft 42 a pawl carrying lever 40 carrying at its upper end a pawl 70 which overlies and engages the teeth of ratchet wheel 72. Lever 40 has pivoted thereto at its lower end a rod 44 which at its forward end carries a slotted member 46. Mounted for free rotation on a shaft 54 supported by bracket bearing means affixed to the loomsides is bell crank lever 52 having a pin 50 riding in the slot 48 of member 46. At the end of the other arm 56 of lever 52 there is pivotally connected a draw rod 58. Referring to Fig. 1, it will be seen that the draw rod carries at its forward end a slotted head 58a in the slot of which rides a draft bracket 60a mounted on a lay sword 60.

As the lay sword oscillates forwardly and back in the loom, bracket 60a will cyclically first positively draw head 58a and rod 58 forwardly to a fixed position, and then allow rod 58 to be moved rearwardly. As rod 58 is drawn forwardly, lever 52 is rocked, moving pin 50 to the lower end of slot 48 and then drawing rod 44 forwardly (to the left in the drawings). In turn, rod 44 rocks lever 40, causing pawl 70 to rotate ratchet wheel 72 and eccentric 74. Overthrow and retrogressive rotation of ratchet wheel 72 are prevented by a friction band 73 substantially encircling friction flange 72c and secured to any fixed structure of the loom, such as a bearing supporting bracket 92 to be later described. Thus eccentric 72 is intermittently rotated in small steps, carrying ring gear 76 around in its orbit about shaft 42. Since ring gear 76 is restricted as to rotation about its own axis by the action of member 80 on lugs 76a, the ring gear will as it moves through its orbit, rotate gear 78, with whose teeth it engages. Gear 78 is thus rotated in small steps, at a lower rate of revolution than that of ratchet wheel 72. With pawl 112 in engagement with a tooth 114 on gear 78, pawl wheel 111 will be rotated in unison with gear 78, and will in turn rotate shaft 42 and pinion 82. Thus warp beam 16 will be slowly rotated in a direction to let off warp 18.

Reference to Figs. 1 and 7 will show that while the lay sword causes a positive driving movement of rod 58, lever 52, rod 44 and lever 40 each to a prescribed position at each forward movement of the sword, the non-driving or return movement of these parts is not positive due to the lost-motion connections at slotted head 58a and at slot 48. Hence by governing the extent of return movement of lever 40 the average rate of rotation of the ratchet wheel 72, and hence of beam 16, can be regulated. This regulation of the rate of rotation is effected in accordance with two factors, namely, the tension of the warp sheet extending from the warp beam and the diameter of the warp mass on the beam 16. These two regulating functions and the means for effecting them will now be explained.

Referring to Figs. 1 and 5, it will be noted that the warp sheet 18 extending from the warp mass on beam 16 passes upwardly and over a whip roll 20. The whip roll is journaled on arms 22 having shaft-like extensions 25 resting in saddle bearings or seats in arms 23 secured on a transverse shaft 24 extending across the loom beneath the warp sheet. Shaft 24 is journaled in saddle bearings in brackets 26 affixed to the loomsides. Only those of members 22, 23, and 26 at the right hand side of the loom are shown, it being understood that similar complementary members are provided at the opposite side of the loom. An arm 13 is fixed on extension 25 at the right hand loomside, and rests on a bracket 11 affixed to the loomside 10, to limit rotation of arms 22 and the whip roll about the axis of extensions 25 under the force of the warp sheet on whip roll 20. Shaft 24 has affixed thereon at the right hand loomside a depending arm 28. Referring to Figs. 1 and 7, it will be noted that arm 28 has pivotally attached thereto at its lower end a rod 30. This rod is provided with a collar, preferably of two-piece adjustable construction. Adjustably affixed to the loomside 10 is a bracket 39 having an abutment 34 having a guide hole through which rod 30 is arranged to slide. On rod 30 and between abutment 34 and collar 32 there is provided a compression spring 36. This spring tends to maintain the rod 30, arm 28 and arms 23 in position with whip roll 20 pressed tightly against the warp sheet, but allowing the whip roll to move in response to variations in tension in the warp sheet. Pivotally mounted as on a pivot 39a on bracket 39 is a depending lever 38 carrying a pivot pin 38a on which is journaled the lower end of rod 30. Referring to Figs. 4 and 7 it may be seen that levers 38 and 40 are provided with opposed channeled lever arms in the channels of which is arranged an adjustable transmitter 68. This transmitter is arranged to be vertically positioned by means described hereinafter, and is effective, in any of its several positions, to transmit forces from either of the levers to the other. Thus at each forward beat of the lay sword lever 40 is rocked clockwise to a prescribed position, and lever 38 is, through the transmitter 68, rocked counterclockwise. As the lay sword moves rearwardly and allows the linkage connected thereto to partake of return movement, the extent to which pawl carrying lever 40 is returned is governed first by the extent to which the warp sheet tension causes lever 38 to return under the counteracting pressure exerted by spring 36, and secondly by the vertical position of transmitter 68 in the channels of the two levers. It is evident that the lower transmitter 68 is in the channels, the greater is the resultant return movement of lever 40 for a given extent of return movement of lever 38.

From the above it is seen that the return movement of pawl carrying lever 40 is regulated by the tension in the warp sheet, being greater in response to increase in warp tension and less in response to decrease in warp tension.

Since the warp mass on warp beam 16 decreases in diameter as the warp is used, means for increasing the rate of rotation in accordance with the decreasing diameter of the warp mass must be provided. The structure provided for this purpose comprises an arm 62 secured on the inner end of shaft 54 and having a shoe or runner bearing against the warp mass on the beam. As the runner follows the surface of the warp mass inwardly as the diameter of the latter

decreases, shaft 54 is slowly rotated. This slow rotation is imparted to an arm 64 secured at one end to the shaft near its outer extremity. At its other end arm 64 is pivotally connected to a bar 66 carrying at its upper end the aforementioned transmitter 68. It thus is seen that the vertical position of transmitter 68 in the opposed channels of levers 38 and 40 is governed in accordance with the diameter of the remaining warp mass on beam 16; and that as the diameter decreases transmitter 68 is slowly lowered to cause a gradual increase in the extent of the non-working or return strokes of pawl carrying lever 40. Thus the rate of rotation of the warp beam is slowly increased to compensate for gradual decrease in diameter of the warp mass.

The structure hereinabove described operates to regulate the rate of rotation of the warp beam in accordance with the tension in the warp sheet and in accordance with the decrease in diameter of the warp mass, and may be of the type and construction commercially employed on many looms.

Relatively large variations in the tension in the warp sheet occur during each weaving cycle, such variations being caused by the reed beating up the weft yarn, and by the action of the harness motion in shedding the warp threads. The maximum tension produced may be sufficient to cause parting of many of the warp threads if not relieved. The structure provided by the present invention is directed toward the relief of increases in warp sheet tension; and as shown in a preferred embodiment of the invention illustrated in the drawings, relieves the cyclical tensioning of the warp sheet by allowing the warp beam to oscillate about its axis.

In prior constructions of the let-off previously described, the slot in the lower end of member 80 was fitted over the end of shaft 54, allowing member 80 to reciprocate in a diagonal direction with shaft 54 riding in the slot and restraining member 80 from rotation. According to the invention, member 80 is permitted to oscillate in response to the variations in torque applied to it from the warp sheet through pinion 82, shaft 42, pawl wheel 111, gear 78 and ring gear 76 whose lugs 76a engage in slots 76b of member 80. Referring to Figs. 1 and 3, a shaft 86 is slidably mounted in holes formed respectively in a bracket 90 and an arm 98. Bracket 90 is secured as by bolt means 94 to an outboard bearing bracket 92 affixed to the loom frame, and acts as a fixed guide for shaft 86 while permitting loose movement of the latter. Arm 98 is affixed to shaft 54 and serves to loosely guide the shaft 86 at the end opposite bracket 90. Shaft 86 is pierced to form a hole transversely therethrough for the reception of a bolt 88. The shaft may be flattened at and near the region of the hole, as indicated in Fig. 4. Bolt 88 is passed through the hole, through the slot in the lower end of member 80, and has applied thereto a washer and nut, as shown in Fig. 4. The connection thus made between shaft 86 and member 80 is relatively loose so that bolt 88 may slide freely in the slot and not cause shaft 86 to be raised or lowered as member 88 rises and falls in the normal course of its movements. A collar 96 is fixed on shaft 86 to prevent excessive movement of the shaft rearwardly in the guides. A second collar 102 is fixed on the shaft and serves as an abutment against which a compression spring 104 bears. The other end of this spring presses against arm 98.

As hereinabove indicated, the tension in the warp sheet produces a torque on the warp beam, which torque is transmitted to ring gear 76. That gear tends to rotate member 80 about shaft 42 in a counterclockwise direction as viewed in Fig. 6 of the drawings, with a degree of torque proportional to the tension in the warp sheet. In let-off mechanisms prior to the present invention the torque applied to member 80 was countered by forces acting on member 80 by shaft 54, which rode in the slot in the lower end of the member. Member 80 did not yield under excessive warp sheet tension, with the result that a yielding whip roll was necessary with the prior constructions above mentioned. According to the present invention, member 80 moves as soon as torque is applied by the ring gear, rotating clockwise and compressing spring 104 until the back pressure exerted by the spring balances that produced on bolt 88 by the mentioned torque on member 80. Thus variations in tension in the warp sheet during the weaving cycle are transmitted to member 80, which oscillates about shaft 42 as an axis in response to the variations in warp sheet tension. As member 80 oscillates, ring gear 76 and the other gearing connecting the ring gear with the warp beam 16 also oscillates; and the warp beam oscillates accordingly, relieving the increases in warp sheet tension and absorbing decreases in that tension. Since the torque arm measured by the distance between shaft 42 and bolt 88 is not varied as member 80 is raised and lowered in response to orbital movement of ring gear 76, the counter-torque applied to member 80 by spring 104 is constant for any particular degree of compression of the spring; and the oscillations of member 80 will accordingly be generally uniform over a long period of time.

As the warp sheet is unwound from the beam 16 and the diameter of the remaining warp mass decreases, the torque applied to the gearing by the warp sheet tension will decrease, owing to the decreasing effective length of the lever arm to which the tensile forces are applied. As a result of this gradual decrease in torque, member 80, Fig. 3, would gradually move counterclockwise about shaft 42 in its oscillations. This movement is obviated by a gradual relieving of spring 104 by the gradual clockwise rotation of arm 98 as beam follower 62 maintains contact with the decreasing warp mass on the beam. Hence member 80 may remain in a generally vertical position as it partakes of its relatively rapid oscillatory movements and its slower rise and fall movements.

From the above it will be seen that the invention provides means whereby the warp sheet may be positively let off from the warp beam at a closely regulated rate, and the tension thereof held closely to a fixed desired value throughout the feeding of an entire beam of warp, and whereby the warp sheet tension is maintained substantially constant throughout the weaving cycle of the loom.

Having disclosed a preferred embodiment of the invention it will be evident that changes and modifications thereof will occur to those skilled in the art, and what I claim and desire to secure by Letters Patent of the United States is:

1. In a warp let-off mechanism for a loom having a warp beam from which extends a warp sheet subject to repeated variations in tension, in combination therewith: forwardly and reversely operable means including a shaft and gearing carried by the shaft and arranged for rotation in a

forward direction to permit forward rotation of the beam to let off warp from the beam and arranged for rotation in the reverse direction to reversely rotate said beam to wind warp thereon, said gearing including a first gear rotatable about the shaft axis and a planetary gear in engagement with said first gear; power means acting to impart planetary motion to said planetary gear; an oscillatable member straddling said shaft and engaging and restricting rotation of said planetary gear about its own axis to cause the planetary gear to drive said first gear incident to action of said power means, said member in turn having torque imparted thereto by said planetary gear, and means engaging said member and including a spring arranged to be stressed by movement of said member in one direction caused by increase in torque applied to said member upon forward rotation of said gearing and beam incident to increase in warp sheet tension, said spring arranged and acting to oppositely move said member and reversely rotate said gearing and beam upon decrease in said torque incident to decrease in warp sheet tension, whereby said warp beam is oscillated in response to said repeated variations in warp sheet tension to reduce the magnitude of said variations.

2. In a warp let-off mechanism for a loom having a warp beam subjected to a fluctuating torque by a warp sheet whose tension fluctuates; gearing including a planetary driving gear and engaging said warp beam to transmit torque thereto and therefrom, said planetary gear tending under applied torque to rotate about its own axis and being subjected to fluctuating torque transmitted from said beam; operating means intermittently driving said gearing and beam to intermittently let off the warp sheet; and yieldable means yieldingly restraining said planetary gear from rotation about its own axis, said yieldable means including a resilient member arranged to yield in response to increase in said transmitted torque incident to increase in warp sheet tension and to return in response to subsequent decrease in said transmitted torque incident to decrease in warp sheet tension; whereby said warp beam is oscillated in response to said fluctuating warp sheet tension to reduce the magnitude of the fluctuations.

3. In a loom having a warp beam and a warp sheet being drawn therefrom under tension, means for rotating said beam to let off warp therefrom which includes intermeshing gears and a ratchet wheel and pawl and means for actuating said pawl for intermittently advancing said gearing, and means for controlling the rotation of the warp beam as advanced by said pawl and ratchet wheel to relieve excessive tension in the warp sheet and to increase tension therein when the warp tends to become too slack, said means functioning through said intermeshing gears and comprising an arm attached at one end for movement with one of said gears and an anchor means for the opposite end of said arm comprising a resilient means by which the arm is restrained to oscillate under forces imparted through said gears within a predetermined angular extent.

4. In a loom having a warp beam and a warp sheet being drawn therefrom under tension, means for rotating said beam to let off warp therefrom which includes intermeshing gears one of which is a planetary gear, and a ratchet wheel and pawl and means for actuating said pawl for intermittently advancing said gearing, and other means for controlling the rotation of the warp

beam as advanced by said pawl and ratchet wheel to relieve excessive tension in the warp sheet and to increase tension therein when the warp tends to become too slack, said means functioning through said intermeshing gears and comprising an arm attached at one end for movement with said planetary gear and an anchor means to which the opposite end of the arm is connected, said anchor means comprising a resilient means by which the arm is restrained to oscillate under forces imparted through said gears within a predetermined angular extent.

5. In a loom having a warp beam and a warp sheet being drawn therefrom under tension, means for rotating said beam to let off warp therefrom which includes a plurality of intermeshing gears one of which is a planetary gear, and a ratchet wheel and pawl and means for actuating said pawl for intermittently advancing said gearing comprising connections to the pawl from the reciprocating lay mechanism of the loom, and other means for controlling the rotation of the said warp beam as advanced by said pawl and ratchet wheel to relieve excessive tension in the warp sheet and to increase tension therein when the warp tends to become too slack, said controlling means functioning through said intermeshing gears and comprising an arm having one end thereof formed as a crosshead and means between said planetary gear and crosshead for preventing relative rotation between the two, and an anchor means to which the opposite end of the said arm is connected, said anchor means comprising a resilient connection and stop means, said resilient connection and stop means being so devised as to limit the extreme angular oscillation of the arm and planetary gear and for resiliently limiting that oscillation within a predetermined angular extent.

6. For a let-off for a loom having a warp beam and a warp sheet drawn from said beam under tension, said let-off comprising a train of gears one of which is a planetary gear and pawl and ratchet means for advancing said train of gears, a means for preventing relative rotation of said planetary gear beyond a relatively small angular extent and for relieving excessive tension in the warp sheet and increasing tension therein when the warp tends to become too slack, comprising an arm and means between said planetary gear and arm for preventing relative rotation between the two, and an anchor means for the opposite end of said arm comprising a resilient connection thereto for restraining the oscillation of the arm within a relatively small angular extent.

7. For a let-off for a loom having a warp beam and a warp sheet drawn from said beam under tension, said let-off comprising a train of gears one of which is a planetary gear and pawl and ratchet means for advancing said train of gears, a means for preventing relative rotation of said planetary gear beyond a relatively small angular extent and for relieving excessive tension in the warp sheet and increasing tension therein when the warp tends to become too slack, comprising an arm having at one end a cross head, inter-engaging means between the planetary gear and the crosshead for preventing relative rotation between the gear and arm, and an anchor means for the opposite end of said arm which comprises a rod member, a connection between the arm and rod member, stop means for limiting movement of the rod in one direction and resilient means for restraining the rod and the arm thereby to pre-

75

9

vent movement of the arm and planetary gear beyond a relatively small angular oscillation therefor.

WALLACE HAMILTON.
